W. D. RUNDLETT.

SPINNING MULE.

APPLICATION FILED OCT. 7, 1909.

953,801.

Patented Apr. 5, 1910.

UNITED STATES PATENT OFFICE.

WILLIAM D. RUNDLETT, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

SPINNING-MULE.

953,801.

Specification of Letters Patent. Patented Apr. 5, 1910.

Application filed October 7, 1909. Serial No. 521,492.

To all whom it may concern:

Be it known that I, WILLIAM D. RUNDLETT, a citizen of the United States, and resident of North Andover, county of Essex, 5 State of Massachusetts, have invented an Improvement in Spinning-Mules, of which the following description, in connection with the accompanying drawing, is a specification, like characters on the drawing 10 representing like parts.

This invention relates to spinning mules and more particularly to the so-called quadrant-mechanism, in which the quadrant is provided with a screw rotated automatically 15 by suitable means including an intermittently-acting member such as a feed-band or rope which is moved longitudinally when the tension of the yarn demands it, to thus effect the feed of the quadrant-nut coöperating with the screw. Said nut has a sheave over which passes the winding chain connected with the spindle-driving drum, means 20 being provided to oscillate the quadrant with a constant stroke throughout the winding 25 of a set of cops, all in a manner well known to those skilled in the art.

The feed-band is in practice carried around a sheave rotatably mounted on the usual reciprocating carriage, and ordinarily 30 the band is inactive, *i. e.* it has no longitudinal movement as the carriage reciprocates, but such reciprocation, in conjunction with the engagement of the feed-band and sheave, causes the latter to rotate. When such rotation is stopped, however, the feed-band is 35 in a manner held from movement relatively to the carriage and hence is caused to travel longitudinally and thereby to effect, through suitable gearing, the rotation of the quadrant-screw and consequent feed of the co- 40 operating nut. Such stoppage of rotation of the rotatable member or sheave on the carriage is controlled by or through the faller-motion, which comprehends a guide faller to guide the yarn to position and a tension faller to retain the yarn under tension, both mounted on the carriage and ordinarily controlled by weights, the fallers being provided with rocking arms to raise 45 and lower the feed-controller chain.

Both the feed-band and the sheave rotated thereby are idle or inactive, so far as concerns the performance of any function, when the feed-band is quiescent and the sheave 50 rotates, but when the rotation of the sheave

is stopped and consequent longitudinal movement of the feed-band is effected both of said parts become active to effect the operation of the feed-motion, as will be apparent.

60

Ordinarily stoppage of rotation of the sheave is effected by engaging the same with a pawl properly guided and supported by the usual carriage, operated and controlled by the fallers, as for instance in United States Patent No. 866,307 granted to me September 17, 1907.

65

Briefly describing the operation, if the yarn is being wound too fast the strain thereupon draws down the tension faller, 70 rocking its arm, and through the feed-controller chain the pawl drops into engagement with and stops rotation of the sheave on the carriage, so that as the latter moves the feed-band is moved and by intervening mechanism, turns the quadrant-screw and feeds the nut thereon. This results in the unwinding of less chain from the chain-drum and the spindles are turned less rapidly, reducing the amount of yarn being 75 wound and allowing the tension faller to rise, or to descend less rapidly, according to the degree of control demanded.

75

The descending movement of the faller controlling the tension on the yarn is very 80 gradual, while it will be apparent that the operation of the means which sets up or brings about the functional movement of the normally quiescent member of the feed-motion must be practically instantaneous if 85 durability and sureness of action is to be maintained. This is impossible in the structures now known to me when operated from a slow moving source, such as the faller, and

90

as a matter of actual practice the excessive wear of the pawl and ratchet device now in use, and its more or less faulty operation, is due to the fact that such coöperating parts are brought into partial engagement and disengagement often a number of times before the complete engagement is effected. There is no instantaneous and complete engagement of such parts, and it cannot be, except accidentally and occasionally, in the 95 mechanism now in use, and my present invention has for its object the production of means whereby the objections hereinbefore

95

set forth are effectually overcome and a complete and instantaneous coöperation of the parts is effected when demanded.

100

105

110

In one practical embodiment of my invention shown and described herein, the means which brings about the operation of the feed-motion is, for illustrative purposes, 5 shown as having two members which are to operatively engage, one being movable with relation to the other, but one of said members is held or locked stationary with relation to and out of engagement with the other 10 member, such relatively stationary member being released when demanded by the tension of the yarn, and its functional movement is at once and instantly effected by actuating means independent of and separate 15 from the faller. As a result the speed of movement of the faller has nothing to do with the relative movement of the co-operating parts into instant, full and complete operative engagement, so that the desired object is attained and objections heretofore 20 present in such portions of a mule structure are eliminated.

For illustrative purposes and for convenience I have herein shown the co-operating 25 parts or members as a pawl and a ratchet, and embodying in the general mode of operation one entirely practical and successful form of my invention.

The novel features of my invention will 30 be fully described in the subjoined specification and particularly pointed out in the following claims.

Figure 1 in side elevation and section shows a sufficient portion of a mule to be 35 understood, with one practical embodiment of my present invention applied thereto, the feed-motion being inactive; Fig. 2 is an enlarged detail in side elevation of the novel structure illustrated in Fig. 1 and in the 40 same position as therein shown; Fig. 3 is a similar view but showing the parts in position to effect the functional or longitudinal movement of the feed-band and thereby cause the feed-motion to operate; Fig. 4 is a 45 left-hand end elevation of the mechanism shown in Fig. 3; Fig. 5 is a diametrical section of the member co-operating with the feed-band and by or through which said band is rendered active; Fig. 6 shows side 50 and edge views of one part of the locking or detent device, to be referred to; Fig. 7 shows similar views of the other part of such device.

Referring to Fig. 1, A is a part of the 55 usual reciprocating mule-carriage having spindles, as A', and a spindle-driving drum A²; B is the shaft of the tension faller and B' its connected arm; C is the shaft of the winding or guide faller, with a connected 60 arm C', and C² is a chain or other flexible connection suspended from said arms and carried around a sheave a on a rod a' movable longitudinally in a guide a² mounted on the carriage, the connection C² being sometimes 65 termed the feed-controller chain, all of

said parts being of usual construction and substantially as in my patent referred to.

The quadrant D, quadrant-screw D' and its nut D² provided with sheave D³, the chain D¹⁰ operatively connected with the 70 usual winding drum of the mule carriage from which the spindles derive their movement during winding; the belt wheel or sheave d⁷ and the gearing D^x (see dotted lines Fig. 1) between it and the quadrant-screw, to rotate the latter; the wheel or sheave d¹² mounted on the stationary stand d¹⁰, sheave d¹⁴ rotatably mounted on a casting d¹³ secured to the carriage A, and the endless rope, belt or feed-band d⁸, are all of 80 well known construction.

The sheaves d⁷ and d¹² receive the feed-band, which latter between said sheaves is passed partially about the sheave d¹⁴ and a second sheave d¹⁶, all of said wheels or 85 sheaves in practice being grooved to properly receive the feed-band, which band, with the gearing D^x constitute an instrumentality commonly termed the feed-motion, intermittently active to effect rotation of the 90 quadrant-screw.

Normally the sheaves d¹⁴, d¹⁶ rotate freely or idly on their axes as the carriage reciprocates and at such time the feed-band performs no function, it being quiescent and 95 having no longitudinal movement, but when the rotation of the member or sheave d¹⁶ is stopped the functional movement of said band is effected, for then it is in a manner held to or connected with the carriage and 100 is caused to move longitudinally.

The member or sheave d¹⁶ and the member or device for stopping the rotation thereof constitute, broadly speaking, the essential 105 elements of means to cause the feed-motion to act, for when such members are in operative engagement the functional or longitudinal movement of the feed-band is at once set up through the travel of the carriage. Herein, while these members are relatively 110 movable one of them is normally stationary with relation to and disengaged from the other, and during such time the feed-motion is inactive, as will be manifest.

In the present embodiment of my invention the band-engaging member d¹⁶ has its hub 1 elongated to receive a ratchet 2, the parts being locked to rotate together by a lug 3 on one entering a recess 4 in the other, Fig. 5, and a short-hooked arm 5 is fixed on the outer end of the stud 6 on which the sheave and connected ratchet rotate, but this particular structure may be modified as to its details without departing from my invention, and I consider the sheave d¹⁶ and its connected part 2 to constitute the member which rotates when the feed-motion is inactive.

Upon a lateral stud 7 projecting from the casting d¹³ above said rotatable member I 120

5 pivotally mount the relatively movable stopping member or stop, shown as a pawl 8 having its free end shaped at 9 to squarely and firmly engage one of the ratchet teeth, as
 10 in Fig. 3, the engaging or functional movement of said member 8 being effected by a suitable spring 10, constituting an actuator, connected at one end with the fixed arm 5 and at its other end connected, as will be de-
 15 scribed, with an upward extension 11 on the pawl, at one side of its fulcrum stud 7.

When the rotatable and stopping members are relatively stationary and disengaged, Figs. 1 and 2, the actuator is under tension
 15 but is held from acting by a locking or detent device, to be described, but when said device is rendered inoperative and the parts are released or unlocked the functional movements of the actuator 10 and the stopping member 8 instantly occur, and a quick, sharp and positive engagement of the pawl and ratchet occurs, instantaneously stopping the rotative movement of the sheave d^{16} and simultaneously setting up the operation of
 20 the feed-motion by or through the travel of the mule carriage.

Upon the stud 7 between the pawl 8 and the casting d^{13} is fixed, by a set screw 12, a keeper 13, shown separately in Fig. 7, having
 25 a stop shoulder 14 and an adjacent curved surface 15, and in the extension 11 I provide a headed pivot pin 16 on which is secured a detent, dog or latch 17, having a tooth 18 to at times coöperate with and be held by the stop shoulder 14, see Fig. 2. The detent has a tail 20 extended beyond the fulcrum pin 16, provided with an elongated slot 21, best shown in Fig. 6, the detent and pin 16 rocking in unison. The detent and
 30 the shouldered keeper constitute a locking or detent device to maintain the stopping member 8 locked stationary in inoperative position, as shown in Figs. 1 and 2, at such time the tooth 18 engaging and being held
 35 by the shoulder 14 so that the member 8 is held up in stationary position and out of engagement with the toothed or ratchet portion of the rotatable sheave d^{16} .

From an inspection of Fig. 2 it will be manifest that as long as there is any co-operation between the parts 14 and 18 the locking device will be operative and the stopping member will be held stationary relatively to and out of engagement with the
 40 rotatable member, the spring 10, attached eccentrically to the head of the fulcrum pin 16 at 19, acting to hold the detent securely in coöperative engagement with the keeper. At the instant of disengagement of the parts
 45 14 and 18, however, the locking or detent device becomes inoperative, the stopping member and actuator 10 are released from its control, or unlocked, and instant movement of the stopping member takes place,
 50 with practical simultaneous engagement with

and stoppage of rotation of the rotatable member, the parts just referred to then assuming the relative positions shown in Fig. 3. The feed-band is now held or connected with the carriage in such manner that longitudinal movement of the band, and consequent operation of the feed-motion, is effected and the quadrant-screw will be rotated to effect feed of the nut D^2 .
 55

While the operation of the means to cause the feed-motion to act is directly effected by or through the actuator 10, as herein shown, such operation is controlled as to the time it shall act by or through the tension of the yarn, acting through the faller motion. 80

The longitudinally movable rod a' herein-before referred to has in previous structures had secured to or forming a part of it the pawl or tooth arranged to engage the ratchet connected with the sheave or rotatable member d^{14} , as in my prior patent said rod being elevated by or through a pull on the flexible member or chain C^2 and depressed by a spring, as a^3 , when the chain is slackened. Herein, while the movement of said rod is 90 effected as heretofore the stopping member or pawl is not mounted thereon, but is a separate device, (see the member 8 herein) and performs its functional movement independently of the movement of said rod. 95

Referring to Figs. 2 and 3 the lower end of the rod a' has fixed thereto a laterally extended pin or stud 22 which loosely enters the slot 21 in the tail 20 of the member 17 of the locking device, and hence has a lost-motion connection therewith equivalent to the difference between the length of the slot and the diameter of the pin. 100

In the position of the parts shown in Figs. 1 and 2 it is supposed that the yarn tension 105 acting through the faller motion has brought about a descent of the rod a' until its pin 22 is at the bottom of the slot 21, and any further descent will then operate to turn the dog or latch 17 with its fulcrum pin 16 against the action of spring 10, to disengage the tooth 18 from the stop shoulder 14. When this disengagement is complete the actuator 10 instantly throws the stopping member 8 into engagement with the ratchet 2, as shown 110 in Fig. 3, and the dog 17 will be moved thereby into the position illustrated, the tooth 18 then bearing upon the top surface of the stop shoulder 14 and being held there by the pull of the spring. It will be seen 115 that during this operation the member 8 has moved absolutely independently of the rod a' , and that the pin 22 thereon is now at the upper end of the slot 21, Fig. 3, and during the actual functional movement of the stopping member 8 it is entirely free from the control of the faller-motion, and is actuated by the spring 10, giving the desired quick action irrespective of the speed of the rod a' forming a part of the controlling connection 120 125 130

governed by the faller motion. Thus while the unlocking or release of the stopping member and its actuator is controlled and brought about by the fallers the actual operation after unlocking is wholly independent of the fallers, thereby differing absolutely from prior devices of this character known to me, for in such devices the fallers at all times directly control and govern the movement of the stopping device.

The unlocking or release in accordance with my invention is sudden and complete at a specified faller position, and then the parts act independently of the fallers, but as shown in Fig. 3 the parts involved are so related that any considerable upward movement of the faller will disengage the stopping member from its coöperating member, for the pin 22 is at the upper end of the slot 21, and the first uplift of the rod a' will lift the member 8 out of operative position, because the tooth 18 is on the upper surface of the stop shoulder 14. Continued upward movement of the rod a' will then cause the tooth 18 to drop down behind and in locking engagement with the shoulder, and the stopping member will be locked, as in Fig. 2. When additional upward movement of the rod a' occurs the tooth 18 will slide along the cam surface 30 as the dog 17 and pawl 8 rock upward in unison about the fulcrum stud 7 as a center.

The functional movement of the member 8 when unlocked takes up the lost-motion in 35 the connection between the fallers and the locking device and thereby again places the stopping member 8 under the direct control of the faller motion, so that the member 8 is rendered inoperative when further feed of 40 the quadrant-nut is not demanded, as evidenced by a higher position of the tension faller. Thus the re-setting or locking of the parts is effected. While it is not necessary that such re-setting should be effected by or 45 through the faller motion I have in the present embodiment of my invention shown the apparatus so arranged and constructed as to effect the re-setting in a simple and efficient manner.

In the operation of the mule, during the winding motion and when the fallers reverse their motion at the rolls, the fallers move successively in opposite directions, and during that part of the winding in which 55 the feed takes place the fallers move simultaneously, and in opposite directions. The short arm C' of the guide faller moves upward while the long arm B' of the tension faller moves downward, and the descent of 60 the rod a' is a differential movement due to the different lengths of said arms. When the fallers are reversed from winding to spinning position the tension faller is first depressed and immediately thereafter the 65 winding faller rises and locks the tension

faller against further rise. Under such circumstances rise of the rod a' is due to the movement of the shorter arm C' through a greater arc than that traversed by the arm B' . At the time of winding, or during the feed period, the arm C' moves through a comparatively short arc and any considerable angular movement of the arm B' acts, on account of its greater radius, to bring about the engagement or disengagement of 75 the stopping member and its coöperating rotatable member. These movements of the guide and tension fallers are apparently, but not in practice, contradictory, for during the feed period the operation of the stopping member is brought about by the descent of the tension faller and it may be rendered inoperative by a corresponding rise of such tension faller. During the faller change at the rolls the same direction of movement 80 of the tension faller for an instant brings about the operation of the stopping member for an instant, but it is immediately rendered inoperative and brought to a position of safety by the immediate rise of the 85 guide or winding faller.

Broadly speaking, my invention comprehends means to bring about the operation of the feed-motion to rotate the quadrant-screw, and a locking device to lock such 90 means from operation but which unlocks the same when the tension of the yarn demands rotation of the screw, the locking device being rendered inoperative by or through the faller motion at a predetermined or fixed point in the movement of the tension faller, the means which bring about the operation of the feed-motion being actuated, when unlocked, independently of the fallers. Accordingly my invention 100 is not restricted to the construction and arrangement herein shown and described, as the same is a practical embodiment of the invention selected for illustration, and changes or modifications may be made by 105 those skilled in the art without departing from the spirit and scope of my invention as set forth in the claims annexed hereto.

Having fully described my invention, what I claim as new and desire to secure by 110 Letters Patent is:—

1. In a mule, in combination, a reciprocating carriage, a quadrant-screw, an instrumentality including a member rotatably mounted on the carriage to effect rotation 115 of the quadrant-screw upon stoppage of rotative movement of said member, and stopping mechanism including a stopping member, an actuator directly connected with said stopping member to effect coöperation thereof with the rotatable member, locking means to restrain the actuator from operation, and a device governed by the tension of the yarn and controlling said locking means, to render it inoperative and thereby 120

125 130

release the actuator and cause coöperation of the stopping and rotatable members by or through the actuator.

2. In a mule, in combination, a reciprocating carriage, a quadrant-screw, an instrumentality including a member rotatably mounted on the carriage to effect rotation of the quadrant-screw upon stoppage of rotative movement of said member, and a stopping mechanism including an actuator, locking means to restrain it from acting, and a device governed by the tension of the yarn to unlock said actuator and permit the functional action thereof to operate the stopping mechanism.

3. A mule having a quadrant-screw, and an instrumentality including a rotating member, to effect rotation of the screw by stoppage of rotation of said member, in combination with a stopping member, and a device which normally locks it from movement, but when the tension of the yarn demands rotation of the quadrant-screw unlocks and releases said stopping member and thereby permits the functional movement thereof.

4. A mule having a quadrant-screw, and an instrumentality including a normally quiescent member longitudinally movable to effect rotation of the screw, in combination with means to coöperate with and effect such movement of said member, a device to lock said means from operation, and separate means governed by the tension of the yarn to unlock said first means and permit the operation thereof.

5. A mule having a quadrant-screw, and an instrumentality including a feed-band longitudinally movable to effect rotation of the screw, in combination with a rotatable band-engaging member, a stop to coöperate with said member and hold it from rotation, to thereby effect longitudinal movement of the feed-band, a lock to hold the stop inoperative, an actuator connected with and to operatively move said stop when unlocked, and means governed by the tension of the yarn to unlock the stop and cause it to co-operate instantly with the band-engaging member.

6. A mule having a quadrant-screw, an instrumentality including a member movable longitudinally to effect rotation of the screw, and a tension faller, in combination with means to effect such movement of said member, an actuator for said means, a device to lock the actuator and restrain it from actuating the said means, and a lost-motion controlling connection between said means and the tension faller, to act upon said device and unlock the actuator and thereby cause said means to operate when the faller has reached a predetermined point in its movement, the actuator when thus unlocked being also freed from the control of the faller.

at such predetermined point in the movement thereof and immediately acting independently of said faller.

7. A mule having a quadrant-screw, an instrumentality including a member movable longitudinally to effect rotation of the screw, and a tension faller, in combination with means to coöperate with and effect such movement of said member, a lock to restrain said means from action, and a connection between the lock and the tension faller, to render inoperative the lock and thereby release said means at a definite point in the movement of the faller.

8. In a mule, a quadrant-screw, an intermittently-acting feed-motion to effect rotation of the screw, means to cause the feed-motion to act, including two relatively movable members one of which is normally stationary with relation to and disengaged from the other, and an instrumentality controlled as to its operation by the tension of the yarn to cause relative movement and operative engagement of said members when rotation of the quadrant-screw is demanded.

9. In a mule, a quadrant-screw, an intermittently-acting feed-motion to effect rotation of the screw, and means to cause the feed-motion to act, including two relatively movable members one of which is normally stationary with relation to and disengaged from the other, and an actuator to effect relative movement and operative engagement of said members, combined with an instrumentality controlled as to its operation by the tension of the yarn to bring about the operation of the actuator when rotation of the quadrant-screw is called for.

10. In a mule, a quadrant-screw, an intermittently-acting feed-motion to effect rotation of the screw, and means to cause the feed-motion to act, including two relatively movable members one of which is normally stationary with relation to and disengaged from the other, and an actuating spring connected with one of said members to effect their relative movement and operative engagement, combined with an instrumentality controlled as to its operation by the tension of the yarn independently of said spring, to bring about the operation of the spring when rotation of the quadrant-screw is called for.

11. In a mule, a quadrant-screw, an intermittently-acting feed-motion to effect rotation thereof, a reciprocating carriage, and means thereon to cause the feed-motion to act, including a ratchet rotated by travel of the carriage when the feed-motion is inactive, and a pawl normally stationary with relation to and disengaged from said ratchet, and a device to hold said pawl stationary combined with an instrumentality controlled as to its operation by the tension of the yarn to release and bring about movement of the

pawl into engagement with and to stop rotation of the ratchet when increased yarn-tension calls for rotation of the quadrant-screw.

- 5 12. In a mule, a quadrant-screw, an intermittently-acting feed-motion to effect rotation thereof, a reciprocating carriage, and means thereon to cause the feed-motion to act, including a ratchet rotated by travel 10 of the carriage when the feed-motion is inactive, a pawl to engage the ratchet and stop its rotation, an actuating spring for said pawl, to effect instant engagement thereof with the ratchet, and a pawl-lock which 15 normally locks the pawl out of engagement with the ratchet, but when the tension of the yarn demands rotation of the feed-screw releases and thereby permits the functional movement of the pawl.
- 20 13. In a mule, a quadrant-screw, an intermittently-acting feed-motion to effect rotation thereof, a reciprocating carriage, and means thereon to cause the feed-motion to act, including a ratchet operatively connected 25 with the feed-motion and running idle when the latter is inactive, a pawl movable into engagement with and to stop rotation of the ratchet, and a pawl-lock which normally locks the pawl stationary with relation 30 to and disengaged from the ratchet, but when the tension of the yarn demands rotation of the feed-screw releases and thereby permits the functional movement of the pawl.
- 35 14. In a mule, a reciprocating carriage, a quadrant-screw, a feed-motion, including an intermittently active feed-band, to rotate the screw, and means mounted on the carriage to coöperate with and render active 40 said feed-band, said means including a ratchet coöperating with the band and rotated by travel of the carriage, a pawl to engage and stop rotation of the ratchet, an actuating spring to effect such engagement, 45 and a pawl-lock which locks the pawl out of engagement with the ratchet, combined with a tension faller, and a lost-motion controlling connection between it and said pawl-lock, to cause the latter to unlock the pawl 50 and permit instant engagement thereof with the ratchet by said actuating spring when the yarn tension demands rotation of the quadrant-screw, the lost-motion connection permitting independent movement of the 55 pawl when the tension faller reaches a predetermined point in its movement, retraction of the pawl from the ratchet and subsequent locking of said pawl being effected through the tension faller.
- 60 15. In a mule, a quadrant-screw, a feed-motion to rotate it, including an intermittently active, longitudinally movable member, means to effect movement by said member, comprising two relatively movable members one of which is normally held station-

ary with relation to and disengaged from the other member, and a device which normally locks the stationary member, but which releases it and permits engagement thereof with its fellow member when rotation of the quadrant-screw is demanded, combined with an instrumentality to disengage automatically said coöperating members and restore one of them to the control of the locking device when rotation of the quadrant-screw is 75 to cease.

16. In a mule, a reciprocating carriage, a quadrant-screw, an instrumentality to rotate it, including a feed-band movable longitudinally to operate said instrumentality, and means on the carriage to effect such movement of the band including two relatively movable members one of which is in engagement with and rotated by said band through travel of the carriage, an actuator 85 to effect relative movement of said members to cause their coöperation and consequent longitudinal movement of the band by stoppage of the member engaging the same, and a device which normally prevents relative 90 movement of said members and holds them disengaged, but which releases them and permits their engagement by said actuator when the tension of the yarn demands rotation of the quadrant-screw, combined with 95 means to thereafter disengage said members and restore them to normal condition under the control of the device which restrains them from relative movement.

17. In a mule, in combination, a reciprocating carriage, guide and tension fallers carried thereby, a quadrant-screw, mechanism, including a feed-band, to effect rotation of the screw by or through longitudinal movement of the feed-band, means on the carriage to control the operative movement of said band, said means including a spring-actuated member, and a device to maintain it stationary and inoperative when the feed-band is inactive, and a controlling connection between said device and the faller whereby the spring-actuated member is released to perform its functional movement when increased yarn tension demands rotation of the quadrant-screw, said member 110 during its functional movement being entirely free from the control of the faller, subsequent return of the said member to inoperative condition being effected when the 115 yarn tension diminishes.

18. A mule having a reciprocating carriage, a quadrant-screw, and an instrumentality including a member longitudinally movable to effect rotation of the screw, in combination with means to effect such movement of said member and including a member movable with and also relatively to the carriage, and a device which normally locks said member from such relative movement, but when the tension of the yarn demands 120

125

130

rotation of the quadrant-screw releases and thereby permits the functional movement of said member on the carriage.

19. A mule having, in combination, a reciprocating carriage, a quadrant-screw, an instrumentality including a member adjacent the path of movement of the carriage and movable longitudinally to effect rotation of the screw, means on the carriage to cooperate with and effect such movement of said member by or through travel of the carriage, a lock normally acting to restrain said means from operation, and other means controlled by the tension of the yarn to unlock said first means and permit the operation thereof.

20. A mule having, in combination, a quadrant-screw, an instrumentality including a normally passive member movable longitudinally to effect rotation of the screw, means having a periodical bodily movement longitudinally of said member and also having a different functional movement to render said member active, and a device which normally locks said means from functional movement but when the tension of the yarn demands rotation of the quadrant-screw unlocks said means and permits functional movement of the same.

30 21. In a mule, a reciprocating carriage, a

quadrant-screw, a feed-motion including an intermittently active member, to rotate the screw, and means mounted on the carriage to at times render said member active, said means including a device movable relatively to the carriage, an actuator to effect its functional movement and thereby cause said member of the feed-motion to become active, and a lock to hold said device stationary on the carriage and prevent its functional movement, combined with mechanism to unlock and permit the functional movement of said device when the tension of the yarn calls for rotation of the quadrant-screw.

22. In a mule, in combination, a quadrant-screw and a feed-motion, means to bring about the operation of the latter to rotate the quadrant-screw, and a locking device which locks such means from operation, normally, but which unlocks the same automatically when the tension of the yarn demands rotation of the quadrant-screw.

In testimony whereof, I have signed my name to this specification, in the presence of two subscribing witnesses.

WILLIAM D. RUNDLETT.
